ABSTRACT OF THE DISCLOSURE

Fabric conditioning device in the form of a pressing iron. The instant device is characterized by the provision of temperature responsive means which actuates means for indicating the displacement of the temperature responsive means which displacement is indicative of whether the proper ironing temperature has been reached, either, as the result of a temperature increase or decrease but more significantly as the result of the latter.

BACKGROUND OF THE INVENTION

This invention relates, in general, to ironing devices and more particularly, to indicator structure therefor.

It is well known that the wholehearted acceptance of consumer products, depends on the convenience with which they can be used. To this end pressing irons are provided with temperature setting control knobs which are so located as to be convenient for actuation by the finger or the thumb. As it turns out, this location cannot, usually, be conveniently seen, for determining, when proceeding from one type of fabric to another, if the control is properly set.

One solution to the above-outlined problem has resulted in the provision of indicator mechanism remote from the control knob and at a location more conveniently seen by the operator. Such mechanism, being either mechanically linked to the control knob for positioning thereof or being temperature responsive, provides the user with a guide as to where the control has been set. A typical placement of such indicator mechanism is sub-adjacent the hand gripping portion of the handle structure. This location is not totally satisfactory since the resultant mechanisms employ rotary indicators which are partially hidden by the handle or are so constructed as to necessitate tilting of the iron for viewing.

Accordingly, the general object of this invention is to provide a new and improved clothes pressing device.

It is a more particular object of this invention to provide, in a clothes pressing device, mechanism for correlating the setting of a temperature control therefor, with a conveniently located and, therefore, readily visible indicator.

Another object of this invention is to provide, in a fabric conditioning device, means for correlating the temperature of the pressing surface thereof with the type of fabric to be conditioned, such mechanism being characterized by having temperature responsive means and being further characterized by the converting of rotational movement to movement which is effectively linear.

Still another object of this invention is to provide indicator mechanism for an iron which can be readily installed in existing constructions and which is inexpensive to manufacture.

BRIEF SUMMARY OF THE INVENTION

Briefly, the above-listed objects are accomplished by the provision of temperature responsive mechanism comprising a coiled bimetal which is riveted to a mounting bracket having good heat transfer properties and which

2

bracket is, in turn, secured in a suitable location by existing hardware of the fabric conditioning device. A vertical rod is attached to the coiled bimetal at one end thereof and carries at the other end thereof a horizontally disposed indicator arm. The bimetal is mounted on one side of the device while the free end of the indicator arm is disposed for movement adjacent the opposite end of the device. Thus, rotational movement of the rod is converted to substantially linear movement on the side of the iron most convenient for viewing and in an area not obstructed by the handle structure or any other part of the device. The indicator is visible through a rectilinear transparent window, and for such purposes, is provided with a readily visible, painted surface, the extent of which compensates for deviations for pure rectilinear motion in the movement of the free end of the indicator.

Further objects and advantages of the present invention will become more apparent when considered in view of the following detailed description and drawings.

DESCRIPTION OF THE DRAWINGS

FIGURE 1 is a side elevational view, partly broken away, of a steam iron incorporating the present invention.

FIG. 2 is a top plan view of the iron shown in FIG. 1.

FIG. 3 is a view taken along the line III—III of FIG.

DETAILED DESCRIPTION OF THE PREFERRED EMBODIMENT

Referring now to the drawings, especially FIGURE 1, reference character 10 designates generally a steam iron. The iron 10 comprises conventional components such as a sole plate 11, a shell or cover member 12 and a handle structure 13 secured to the shell structure 12 by a plurality of screws 14. The shell is, in turn, secured to the sole plate by means of a hat-shaped bracket 16 having a threaded stud 17 extending through a water reservoir and the shell 12 and having a nut 19 affixed thereto.

The handle structure 13 comprises a hand gripping portion 21, front post member 22, rear post member 23 and a shell engaging portion 24.

The portion 24, unlike hand gripping portion 21, is not continuous or in other words, has a break intermediate the longitudinal extent thereof. The aforementioned break is concealed by a saddle-shaped escutcheon plate 26 provided with a rectangular transparent window 27 provided for a purpose to be discussed hereinafter. The window, molded from a suitable material, for example, plastic, comprises slots or grooves 28 on either side thereof, which slots or grooves

are in part, delineated by sloping lugs 29 of wall portions 30. The window 27, which fits into a rectangular opening 31 in the plate 26, is captivated therein. The edges of the plate defining the opening 31 are received in the grooves or slots 28 and contained therein through cooperation of the lugs 29 and the top wall 32 of the window 27.

The temperature of a heater structure 33, embedded in the sole plate 11, is controlled by a bimetal element which serves to open and close a pair of contact carrying arms 36 and 37.

To vary the point at which the contact arms 36 and 37 are opened and closed, a control rod is linked, in any suitable manner, to the arm 37. Vertical movement of the rod 38 is accomplished by a control knob 39 and lever arm 41 operatively associated with a rotatable cam and yoke construction, of conventional construction, generally indicated at 42. The knob, lever, cam and yoke are supported in a recessed area 43 of the front post member 22, the recessed area having a cover member 44 thereover.

The cover member 44 has an indicia bearing member 46 carried thereby. The indicia thereon provides means for cooperating with the knob 39 for adjustment of the control rod 38.

act arm 37. In like manner, the escutcheon plate 26 is provided with indicia adjacent the window 27, which corresponds to the indicia of the member 46 and which cooperates with horizontally disposed indicator arm 47 carried by the upper end of a vertically disposed connector rod 48. The opposite end of the rod 48 is secured in a suitable manner, for example, by welding, to a coiled bimetal 49 which upon experiencing a rise in temperature effects counterclockwise rotation (as viewed in FIGURE 2) of the rod 48 and indicator arm 47. Approximately one-half of the arm 47 is painted or colored as indicated at 50 such that it distinctively appears in the window 27. The colored part of the arm cooperates with the indicia disposed adjacent the window to correlate or show correspondence between the setting of the knob 39 with the temperature of the sole plate. The most useful aspect of this arrangement exhibiting itself when alternately ironing fabrics, for example, when a fabric requiring a higher temperature is followed by the ironing of a fabric requiring a lesser temperature. The indicator serves to let the operator know that the iron has sufficiently cooled to avoid damage to the fabric requiring the lesser temperature.

The coiled bimetal 49 has a radially extending segment 51 which is secured to an L-shaped bracket 52 as by rivets 53. The bracket 52, made from any suitable material exhibiting good heat transfer properties, for example, aluminum, is secured in contact with a flange 54 on the bracket 16 and with the existing screw 55 which would normally serve to secure just the flange 54 in place.

The end of the indicator arm 47 opposite the colored portion 50 is turned back on itself as indicated at 56. In the assembled condition as shown, the portion indicated at 56 has an aperture 57 which is aligned with a second aperture 58 in the main part of the arm 47 to permit insertion of the rod 48 therethrough. The bight portion 59 between the portion 56 and the main part of the arm tends to effect misalignment of the aperture 57 and 58 thereby causing a frictional fit of the arm 47 on the rod 48.

Since numerous changes may be made in the above-described apparatus and different embodiments of the invention may be made without departing from the spirit thereof, it is intended that all matter contained in the foregoing description or shown in the accompanying drawings shall be interpreted as illustrative and not in a limiting sense.

What is claimed is:

1. In an iron, in combination,

- a sole plate,
cover structure,
handle structure having a gripping portion extending along the longitudinal axis of said cover structure and sole plate and approximately in the middle thereof, mounting structure secured to said sole plate and adapted to carry said cover structure, temperature responsive means supported to one side of said handle structure, and means for indicating response of said temperature responsive means, said indicating means being viewable at the other side of said handle structure.
2. Structure as specified in claim 1 wherein, said temperature responsive means comprises a coiled bimetal.
3. Structure as specified in claim 2 including, a heat conducting bracket for mounting said coiled bimetal, said mounting bracket being in good heat transfer relation with said mounting structure and secured by the same means that secures said mounting structure to said sole plate.
4. Structure as specified in claim 2 wherein, said indicator means comprises a horizontally movable arm attached at one end to a vertically oriented rod secured to said coiled bimetal, the part of said arm adjacent the free end thereof being visible through a window in said handle structure.
5. Structure as specified in claim 4 wherein, said window is rectilinear and is disposed to the side of said handle structure, whereby it is unobstructed thereby.
6. Structure as specified in claim 5 wherein, the attached end of said arm comprises a resilient segment having an aperture therein for receiving said rod and an adjacent segment of said attached end has an aperture which is aligned with said first mentioned aperture when the rod is also received therein, said resilient segment tending to return to its free position wherein said apertures are not aligned.
